UNITED STATES PATENT OFFICE.

FILLMORE WILLIAMS, OF COLUMBUS, OHIO.

AMUSEMENT DEVICE.

No. 853,666.

Specification of Letters Patent.

Patented May 14, 1907.

Application filed August 22, 1906. Serial No. 331,561.

To all whom it may concern:

Be it known that I, FILLMORE WILLIAMS, a citizen of the United States, residing at Columbus, in the county of Franklin and 5 State of Ohio, have invented certain new and useful Improvements in Amusement Devices, of which the following is a specification.

My invention relates to an amusement device for children and particularly to that class of devices known as merry-go-rounds.

The object of the invention is to provide a cheap and simple device of this class to which motion may be imparted by the children 15 either with their hands or with their feet.

Further objects and advantages of the invention will be set forth in the detailed description which now follows:

In the accompanying drawing: Figure 1 is 20 a plan view of a merry-go-round constructed in accordance with the invention. Fig. 2 is a side elevation of said device. Fig. 3 is a detailed section of a centrally disposed standard hereinafter described, and, Fig. 4 is a detailed view of a modified form of carriage hereinafter described.

Like numerals designate corresponding parts in all of the figures of the drawing.

Referring to the drawing the numeral 5 30 designates an annular base upon which is mounted an annular track 6. Braces 7 8 extend diametrically across this base, the brace 8 being set into the brace 7 as is indicated at 9. A plate 10 is secured by screws 35 11 to the brace 8. Threaded into this plate is a pipe or tubular standard 12. Secured upon the upper end of this tubular standard is a 5 way coupling 13 which receives the standard 12, and four radially disposed arms 40 14. A ring 15 is secured to the outer ends of these arms, it being understood that the structure just described is a fixed one, the coupling 13 being brazed or otherwise secured upon the tubular standard 12 in such 45 manner that it will not rotate thereon. Bars 16 17 which are disposed at right angles to each other have openings 18 formed therein through which the tubular standard 12 passes. At the outer ends these bars 16 50 17 have downwardly extending bifurcated members 19, within which grooved wheels 20 are mounted upon axles 21, said grooved wheels running upon the track 6. Seats 22 are mounted upon the outer ends of these 55 bars, said seats being spanned by straps 23

with which the smaller children may be secured in said seats. Braces 24 extend from the downwardly extending portions 25 of the seats to the ends of the axles 21.

The operation of this form of the device is 60 as follows: The children being seated in the seats 22 grasp the hand rail formed by the ring 15 and by pulling upon said rail impart motion to the device, causing the carriages or 65 seats to travel around upon the track 6 and causing the bars 16 & 17 to rotate about the standard 12. If it be so desired, seats such as are shown in Fig. 4 may be substituted for those shown in Fig. 1 and Fig. 2. In this 70 case pedals 20' are provided, by means of which motion may be imparted to the wheels 70 by the feet of the children.

Braces 30 extend between the downwardly extending portions 19 of the bars 17 and impart additional rigidity to the structure. It 75 is desirable that children should indulge in such amusement as will develop them physically and the present device provides a structure which will tempt them to take considerable bodily exercise in the guise of amusement. If the seats 22 were fixed upon the ends of the bars 16 & 17 in Figs. 1 & 2, it is apparent that only the left arms of the children would be exercised and developed. In order that both arms may be equally developed, I 80 prefer to pivot these seats upon the ends of the bars 16 & 17 as is illustrated at 31 in Fig. 2, by virtue of which construction the seats may be swung to the opposite position to bring the right arms of the children nearest 90 the hand rail formed by the ring 15, it being only necessary to remove the cotter pin 32 of the brace 24 to accomplish this.

From the foregoing description it will be seen that simple and efficient means are herein 95 provided for accomplishing the objects of the invention, but while the elements shown and described are well adapted to serve the purpose for which they are intended it is to be understood that my invention is not limited 100 to the precise construction set forth, but includes within its purview such changes as may be made within the scope of the appended claims.

Having described my invention, what I 105 claim is:

1. In a device of the character described the combination with a plurality of carriages of a fixed annular hand rail about which said carriages are adapted to travel.

2. In a device of the character described the combination with an annular track of a fixed annular hand rail concentric with said track and a plurality of carriages adapted to travel upon said track.
3. In a device of the character described the combination with an annular track of an annular hand rail which is concentric with said track and a plurality of reversible carriages adapted to travel upon said track and around said hand rail.
4. In a device of the character described the combination with an annular track of a annular hand rail concentric with said track, a plurality of carriages, wheels upon which said carriages are mounted and which run

upon said track and pedals carried by said wheels.

5. The combination with an annular track of a fixed annular hand rail a plurality of carriages, wheels upon which said carriages are mounted and which travel upon said track and a plurality of rotating bars upon the outer ends of which said carriages are pivotally mounted.

In testimony whereof I affix my signature in presence of two witnesses,

FILLMORE WILLIAMS.
